UNITED STATES PATENT OFFICE.

FRIEDRICH WILHELM MINCK, OF BERLIN, GERMANY.

MELTING-FURNACE.

SPECIFICATION forming part of Letters Patent No. 650,726, dated May 29, 1900.

Application filed May 28, 1898. Serial No. 682,038. (No model.)

To all whom it may concern:

Be it known that I, FRIEDRICH WILHELM MINCK, manufacturer, a subject of the King of Prussia, Emperor of Germany, and a resident of Thurmstrasse No. 71, in the city of Berlin, German Empire, have invented certain new and useful Improvements in or Connected with Melting-Furnaces, (for which I have applied for patents as follows: in Germany, November 1, 1897; in France, April 25, 1898; in Belgium, April 25, 1898; in Austria, April 28, 1898; in Hungary, April 28, 1898; in England, April 27, 1898; in Italy, April 30, 1898, and in Spain May 5, 1898,) of which the following is a specification.

My invention relates to melting-furnaces; and its object is to provide means whereby steam, smoke, and similar bodies evolved during the alloying operations are discharged through the chimney and prevented from entering the working chamber or laboratory. The operator, therefore, is thus able to precisely observe the stream of melted metal during the alloying operation and to treat the same without being put to inconvenience by the steam, smoke, or other bodies.

In the accompanying drawing a melting-furnace to which the new arrangement is adapted is shown in longitudinal section.

30 *a* is the melting-pot; *b*, the fire-grate; *c*, the ash-pit; *d*, the fireplace; *e*, the outlet for the smoke, steam, &c.; *f*, the chimney, and *g* a store-room for the ashes. The melting-pot *a* is filled with the material to be melted, 35 closed with a suitable cover, and placed in the fireplace *d*. The fireplace is then completely filled with fuel and after the fuel has been ignited is closed by means of a stone plate, as usual. When the material has 40 reached a molten state and is to be subjected to the operation of alloying, the fireplace *d* is opened, the glowing fuel above the melting-

pot *a* removed, the cover of the melting-pot lifted off, and the new protecting apparatus or alloy-hopper *h* suspended in the fireplace 45 *d*. This apparatus is funnel-shaped and rests on the supporting-ring *i* over the space *d*. It is furnished with an opening *k* at the bottom, by means of which a view of the melting-pot 50 is obtainable. To the top of the apparatus *h* handles *l* are attached to facilitate its introduction to and removal from the fireplace. The height of the funnel-shaped apparatus is so regulated that between the bottom of the same and the upper edge of the melting-pot 55 *a* a space *m* is left, through which the steam, smoke, and other bodies, produced during the alloying operation in process, can escape into the outlet *e* and thence to the chimney.

What I claim as my invention, and desire 60 to secure by Letters Patent, is—

The combination in a melting-furnace, such as described, of the vertically-extended hearth *d*, the chimney *f*, the lateral flue *e* substantially near the top of and connecting said 65 hearth with the chimney, a fire-grate *b*, ash-pit *c* below said grate, and an ash-receiving box *g* extending laterally from below said pit and vertically upward beside the hearth, a melting-pot *a* borne upon said grate, the annular 70 supporting-ring *i* at the top of said hearth, and a flaring hopper *h* provided with handles *l* and with an opening *k* of substantially the same diameter as the mouth of the melting-pot, suspended directly over the melting-pot 75 and forming an intermediate space for the escape of noxious gases to the chimney, substantially as and for the purpose set forth.

In testimony whereof I affix my signature in presence of two witnesses.

FRIEDRICH WILHELM MINCK.
